Attorney

UNITED STATES PATENT OFFICE.

ROBERT P. WILLIG, OF PITTSBURGH, PENNSYLVANIA.

WINDOW SCREEN.

Application filed May 20, 1926. Serial No. 110,463.

This invention relates to window screens and aims to provide means in association with a conventional rigid or adjustable window screen to permit the same to be positioned above the upper sash and there maintained.

An additional object of the invention is to provide in combination with a screen means whereby the same may be connected 10 to the cords of one of the sashes and that will permit the screen to be positioned directly upon the top of the sash when the same is lowered, after which the screen may be raised to proper position by raising said 15 sash for thus overcoming the requirement of using a step ladder or other body supporting means for disposing the screen initially at the top of the window frame which is now the case in screens of this general 20 character that have heretofore been used.

A further salient object of the invention is to provide means in combination with a window screen to permit the same to be readily positioned and as readily removed 25 without requiring any skill or undue effort whatever.

Other objects will become apparent as the nature of the invention is better understood the same comprising the novel form, 30 combination and arrangement of parts hereinafter more fully described, shown in the accompanying drawing and claimed.

In the drawing:—

Figure 1 is a fragmentary front elevation 35 of a conventional form of window frame within which is mounted the usual sliding sashes, my screen construction being arranged in position above the top of the upper sliding sash, and a portion of the frame 40 being broken away for more clearly disclosing the means of attachment of the screen to said window cords.

Figure 2 is a longitudinal sectional view 45 through the upper end of the frame and through my screen, for more clearly disclosing the connection between the screen and said sash cord, and

Figure 3 is a perspective view of one of 50 the sash cord engaging members associated with the screen.

Now having particular reference to the drawing, 5 designates a conventional window frame construction within which is slidably mounted the usual sashes, the upper one of 55 which is disclosed in Figure 1 and designated 6. As is well known, said sliding

sashes are counterbalanced by weights (not shown) to which are attached certain ends of cables 7—7 that extend over pulleys 8—8 within the upper end of the frame, said cables then extending downwardly within the frame and being attached to the side bars of 60 said sash 6.

My invention per se constitutes the provision of a screen 9 of rigid or extensible 65 construction as desired, and being of any desired width and that is also so constructed as to permit the same to be mounted within the frame 5 above the top sash 6, when said sash is lowered and to be partially supported 70 in position within the upper end of the frame by resting upon the top bar of said sash.

The end bars of the screen 9 are equipped adjacent their lower ends with means for 75 engaging the inner flights of the cords 7—7 for preventing the screen from dropping inwardly or outwardly of the window when installed, and also for frictionally attaching the screen to said cords. As clearly 80 disclosed in the drawings, said means at the opposite ends of the screen are somewhat closer together than are the inner flights of the cords in order that the cords will be bound between the means as hereinafter described.

These means are designated 10—10 and each consists of a metallic plate 11 constructed at its opposite ends with openings 12—12 to permit the same to be bolted, riveted, or otherwise suitably secured to said end bars of the screen 9. At the outer edge 90 of each plate and intermediate the ends thereof is a forwardly extending arm 14 that is in turn formed with an inwardly 95 extending finger 15 that is of arcuate shape in the direction of its width as clearly disclosed in Figure 3.

As clearly disclosed in Figures 1 and 2, the finger 15 of each plate is adapted to be 100 hooked over the inner flight of the adjacent cord 7 for consequently binding the cord between the plate 11 and inwardly extending finger 15 to provide a frictional connection between the arms and said cords in 105 order that as the sash is raised and lowered the screens will be likewise actuated by reason of the fact that said inner flights of the cords move upwardly and downwardly simultaneously with the actuation of the 110 sash.

It will be readily apparent that the screen

9 may be arranged within the frame when the sash 6 is moved downwardly to its full extent. At this position of the sash the screen 9 is disposed within the frame and 45
5 is rested directly upon the top frame bar of the sash after which the inner flights of the cords 7—7 are pulled inwardly over the fingers 15 of the plates which will then permit the sash to be raised which will slide 10 the screen 9 upwardly to the position disclosed in Figure 1 for thus overcoming the necessity of disposing the screen initially in the position intended. Likewise when it is desired to remove the screen, the sash 15
15 6 may be lowered and in view of the connection between the screen and the inner flights of the cords the screen will also move downwardly for bringing the same in such a position as to facilitate the ready 20 removal thereof.

It will thus be seen that I have provided a highly novel, simple and efficient form of screen for windows that is well adapted for all the purposes heretofore designated 25 and even though I have herein shown and described the particular means whereby the screen may be connected to the inner flights of the usual upper sash cord it is nevertheless to be understood that departures may 30 be had therefrom without effecting the spirit and scope of the appended claims.

Having thus described the invention, what I claim as new and desire to secure by Letters Patent is:—

35 1. In combination with a window screen adapted for positioning within the upper portion of a window frame and adapted to rest on the upper edge of the upper sliding sash, means for operatively connecting the 40 window screen to the inner flights of the usual weight-counterbalancing cord for the

upper sliding sash whereby the screen will slide upwardly and downwardly into the frame simultaneous with the actuation of the upper sliding sash.

45

2. In combination with a window screen adapted for positioning within the upper portion of a window frame and adapted to rest on the upper edge of the upper sliding sash, means for operatively connecting the 50 window screen to the inner flights of the usual weight-counterbalancing cords for the upper sliding sash whereby the screen will slide upwardly and downwardly into the frame simultaneous with the actuation of 55 the upper sliding sash, said means comprising hooks secured on the end portions of the window screen adapted for frictional engagement with said cords.

60

3. In combination with a window screen 65 adapted for positioning within the upper portion of a window frame and adapted to rest on the upper edge of the upper sliding sash, means for operatively connecting the window screen to the inner flights of the 70 usual weight-counterbalancing cords for the upper sliding sash whereby the screen will slide upwardly and downwardly into the frame simultaneous with the actuation of the upper sliding sash, said means comprising hooks secured on the end portions of 75 the window screen adapted for frictional engagement with said cords, each of said hooks comprising a metallic plate secured on the window screen, an arm extending laterally from one side of said plate, the outer end of said arm being disposed inwardly, the inwardly disposed portion being curved transversely.

In testimony whereof I affix my signature.

ROBERT P. WILLIG.
